(57) **CLAIM**

The ornamental design for a combination paint brush scraper and washspunge holder, as shown and described.

DESCRIPTION

FIG. 1 is a front perspective view of a combination paint brush scraper and washspunge holder in one use mode of the device showing my new design;

FIG. 2 is an enlarged front perspective view of FIG. 1;

FIG. 3 is a top plan view of FIG. 2;

FIG. 4 is a bottom plan view of FIG. 2;

FIG. 5 is a front elevation view of FIG. 2, the rear and side elevation views being the substantial equivalent thereof;

FIG. 6 is a front perspective view of a combination paint brush scraper and washspunge holder in an alternate use mode of the device; and,

FIG. 7 is an enlarged front perspective of FIG. 6.

The broken lines depict environmental structures and form no part of the claimed design.
